UNITED STATES PATENT OFFICE.

JOHN N. GOULD, OF FREDERICKTOWN, OHIO, ASSIGNOR, BY MESNE ASSIGNMENTS, TO
THE F. B. ZIEG MFG. COMPANY, OF FREDERICKTOWN, OHIO, A CORPORATION OF
OHIO.

WRINGER.

Application filed June 3, 1921. Serial No. 474,736.

To all whom it may concern:

Be it known that I, JOHN N. GOULD, a citizen of the United States, residing at Fredericktown, in the county of Knox and 5 State of Ohio, have invented certain new and useful Improvements in Wringers, of which the following is a specification.

The invention relates to clothes wringers and more particularly to power driven 10 wringers used in connection with washing machines. The invention has special relation to a safety device for the quick release and separation of the rollers in case of emergency.

15 In the ordinary type of power driven wringers there is constant liability of injury to the operator and also of damage to the mechanism. The danger arises from the difficulty in the ordinary wringer of stopping the operation of the wringer before such injury or damage has occurred, as when 20 an operator's hand is caught between the rolls or clothes are wound about and entangled with the rolls. These conditions 25 have necessitated the development of means for quickly releasing the compression between the rolls. Such safety devices as have heretofore been used to accomplish the quick release of the rolls have been generally inconvenient and uncertain in operation.

30 One of the objects of my invention is to provide a quick operating device combining tensioning means for effecting compression of the rollers with releasing means for relieving such tension and separating the rollers.

35 Another object of the invention is to provide prominently available controlling means by which an operator may effect the instant release of the rolls from any position about the wringer.

40 Another object is to provide a unitary device for causing the release and separation of the rolls, and also for restoring the rolls to operative relation under tension.

45 A further object is to provide a simple construction which is very compact in its arrangement and comprising a minimum of parts without lateral projections to obstruct the efficient and convenient operation of the wringer.

50 Further objects and advantages will be apparent in the following detailed description of a preferred embodiment of my invention

which I have illustrated in the accompanying drawings. It will be understood, however, that in the appended claims I aim to cover all legitimate variations and modifications of the preferred construction illustrated herein, which are within the scope of 60 my invention.

In the drawings, Figure 1 is a side elevation of the wringer equipped with my device. Fig. 2 is an end view showing the parts in normal position for the operation of 65 the wringer. Fig. 3 is a partial elevation of the tensioning and releasing mechanism showing the parts moved partially into position to release the tension upon the rolls. Fig. 4 is an end view of the wringer showing 70 the parts of the releasing device in the extreme position for the release and separation of the rolls.

In the embodiment of my invention herein illustrated, I have shown a wringer as 75 adapted for use in a conventional construction of a mechanical washing machine. The wringer is mounted upon a swinging bracket 10 which carries a gear box 11 housing a conventional gear mechanism adapted to 80 drive the wringer rolls. The bracket 10 may be provided with a tubular extension 12 through which a drive shaft 13 may extend into the gear box 11 for the operation of the gear mechanism. The tubular portion 12 85 may be adapted for pivotal mounting in a suitable support carried by the washing machine. A hand lever 14 may be provided on the upper portion of the gear box for the convenient operation of means controlling 90 the engagement of the drive mechanism actuating the wringer rolls.

Mounted on the upper surface of the bracket 10 are a pair of spaced upright standards 15 and 16 on which are supported 95 the roller bearings and which comprise a frame carrying the releasing mechanism. In the lower bearings 17 and 18, formed on the standards 15 and 16, are journaled the ends of the shaft 19 which carries the lower roll 100 20 of the wringer. One end of the shaft 19 extends through the bearing 17 and has a suitable drive connection with the gear mechanism housed within the gear box 11.

Located above the lower bearings 17 and 105 18, and extending longitudinally in each of the standards 15 and 16 are elongated slots 21 constituting slideways. A second shaft

22, having its ends extending through the slots 21, carries the upper roll 23 normally positioned immediately above and resting upon the lower roll 20. Rigidly mounted 5 upon the ends respectively of the upper and lower roll shafts 19 and 22 adjacent to the gear box 11, are a pair of gears 24 and 25 which interengage when the upper roll is in operative position upon the lower roll, 10 and by which the upper roll is operatively driven.

To secure the rolls in normal relation with the necessary compression for the operation 15 of the wringer, I have provided releasable tension means associated with the movable upper roll and operatively supported upon the standards 15 and 16. Mounted at each end of the upper roll between the roll and the adjacent side of the respective standards, 20 are a pair of bearing blocks 26 and 27 which rotatively engage the shaft 22 and are adapted to control the position of the latter in relation to the slots 21. Each of the bearing blocks 26 and 27 is provided with an 25 upwardly extending spirally corrugated projection 28 adapted to receive in rigid engagement therewith the end of a coiled spring 29.

At the upper end of each spring I have 30 provided a member 30 having also a spirally corrugated projection 31 which is engaged within the upper end of the spiral spring. Each member 30 is laterally bifurcated through its upper portion as at 32, and is 35 also provided with registering transverse apertures 33 extending through both arms of the bifurcated portion of the member. Extending within the bifurcated portion of each member 30 is a swinging arm 34 carrying a cross pin 35 extending through the apertures 33. The upper end of each arm 34 is swingably mounted on a fixed pivot 36 rigidly secured at the upper ends of the standards 15 and 16 respectively.

45 The arms 34 form, with the springs 29 and their rigidly associated end members, pairs of toggle members which, when in alinement parallel with the longitudinal axes of the standards, effect the positive positioning of the upper shaft near the bottom 50 of the slots 21, with the rolls in operative relation. The springs 29 are of such length that when the members are in alinement the springs are somewhat compressed 55 and thereby effect the necessary operating compression between the wringer rolls.

To stabilize the members in alined position and prevent their displacement in the ordinary operation of the wringer, I have 60 flattened the upper faces of the bifurcated members 30 as at 37 and have provided shoulders 38 on the arms 34 which are adapted to engage with the flattened faces 37. By this means when the members are 65 alined, it is necessary to positively swing the

toggle joints to break them and release the rolls. To assure a proper alinement in the engagement of the shoulders and the flattened faces, I have provided a peripheral socket 39 in the lower side of each of the 70 apertures 33, in which the pins 35 are seated when the members are in alinement.

To accomplish the simultaneous operation of the releasing device at both ends of the rollers, I have rigidly connected the pins 35 75 in the toggle joint by a control bar 40. In operation the control bar 40 may be grasped or pushed from either side of the wringer in either direction to break the toggle joints at both ends of the wringer rolls and thus 80 instantly release the upper roll from all tension of the springs 29. By the further movement of the control bar the bearing blocks 26 and 27 are drawn upwardly, being guided by the passage of the upper roll shaft 22 through the longitudinal slots 21 in the standards. By this simple means the rolls are quickly released from compression and separated to any desired degree to permit the quick withdrawal of the operator's hand in case of accident, or to remove clothes which may be entangled about the rolls. To restore the rolls to operative relation under compression, it is necessary only 85 to move the bar into position between the upright standards whereby the upper roll is lowered into operative position and with the alinement of the toggle members spring tension is again applied thereto.

The control bar is sufficiently elevated 90 above the rolls so that it offers no obstruction to the ordinary use of the wringer and by reason of its location is conspicuously in view and instantly available to the operator 95 from any position on either side of the wringer. The length of the bar extending along the entire length of the rolls affords 100 added facility to the operator for quickly grasping and releasing the rolls from tension 105 in case of accident.

110 It will now be apparent that I have provided quick releasing means of a very compact and simple construction which securely holds the rolls in proper operative relation under compression until it may be desired to release them, and that the latter operation 115 may be easily accomplished by the movement of the readily available control bar, thereby instantly releasing the rolls and positively forcing their separation. It will also be observed that the continuous engagement of the interconnected parts and the operation 120 of the toggle action between the members avoids the necessity for the separate replacement of the rolls and the tensioning means 125 in restoring them to operative relation.

I claim as my invention:

1. A wringer comprising a frame, a pair 130 of rolls in said frame, mounting means permitting motion of one of said rolls toward

- and away from the other, and a pair of toggle members supported on each side of said frame in planes transverse to the axis of the rolls, one member of each toggle being longitudinally compressible, and a member parallel to said rolls connecting each pair of toggles substantially at the joint, each pair of toggle members when in alinement being operative to effect compression between said rolls and when broken to release said rolls from compression whereupon the movable roll is free for separation from the other of said pair of rolls by movement in said mounting means.
15. 2. In a wringer, a lower roll having a fixed bearing, an upright support, a movable upper roll slidably engaging said support, a movable bearing carried by said upper roll, an arm pivoted on the upper end of said support, a coiled spring having one end attached to said movable bearing and the other end pivotally connected to the free end of said arm, said arm and spring being swingable into and out of alinement to compress and release respectively said rolls, said pivotal connection between said arm and spring having means to slightly resist the movement of those members out of alinement.
3. In a wringer, a lower roll having a fixed bearing, an upright support, a movable upper roll slidably engaging said support, a movable bearing carried by said upper roll, a coiled spring having one end fixed on said movable bearing, a member fixed on the opposite end of said spring having a transverse aperture and a peripheral pocket opening therefrom, said member having a flat outer extremity, an arm pivoted on the upper portion of said support and having a transverse shoulder adjacent its free end adapted to engage the flattened extremity of said member when said arm and spring are in alined position, a pin carried by said arm and freely engaging the aperture in said member, said pin entering said pocket when said arm and spring are in alined position to allow said shoulder and flattened extremity to engage.
4. A wringer comprising a pair of spaced upright standards having longitudinal slideways, a lower roll stationarily journaled in said standards, an upper roll having engagement with said slideways and movable to and from said lower roll, a pair of movable bearings carried by said upper roll, a pair of arms pivoted on said standards above said bearings, a pair of compressible members fixed on said movable bearings respectively and pivotally connected to said arms, said arms and compressible members forming a pair of toggles adapted to resiliently force said upper roll upon said lower roll when alined, and to release and positively separate said rolls when moved out of alinement, and a cross bar extending between said toggles for swinging the joints thereof simultaneously.
5. In a wringer having a stationary roll and a movable roll, toggle means for releasably forcing said movable roll into tensioned contact with said stationary roll, said means comprising an arm swingable on a fixed pivot, a coiled spring, end members having spirally corrugated portions in rigid engagement with the respective end coils of said spring, one of said end members being pivoted to the free end of said arm and the other forming a bearing for said movable roll.
- In testimony whereof, I have hereunto set my hand.
- JOHN N. GOULD.
